UNITED STATES PATENT OFFICE.

WILLIAM F. KLOSE, OF CHICAGO, ILLINOIS.

MACHINE FOR SHAVING PRINTERS' LEADS, SLUGS, &c.

SPECIFICATION forming part of Letters Patent No. 314,384, dated March 24, 1885.

Application filed July 10, 1884. (No model.)

To all whom it may concern:

Be it known that I, WILLIAM F. KLOSE, a citizen of the United States, residing at Chicago, in the county of Cook and State of Illinois, have invented a certain new and Improved Machine for Shaving Printers' Leads, Slugs, and Furniture; and I hereby declare the following to be a full, clear, and exact description of the same.

10 The object of my invention is to provide a machine by means of which the above-named articles may be automatically reduced in thickness and width by shaving, and with great rapidity and exactness, to any desired size, and 15 without danger of breakage to the article in the operation.

To this end my invention consists in a machine operating by friction to force or draw the said articles moving within a recess, in 20 which they are confined laterally and upon their surfaces, between knives.

My invention also consists in a device to be attached to the shaving-machine by means of which the said articles may be fed to the machine automatically; and my invention still further consists in the construction and combination of the parts by means of which the purpose of the machine is effectually accomplished.

30 In the drawings, Figure 1 represents a side elevation of my machine resting upon a table; Fig. 2, a longitudinal vertical section of the automatic feeding attachment shown as attached to the shaving-machine; Fig. 3, a 35 transverse section of the machine, taken on the line 3 3 of Fig. 1, and viewed in the direction of the arrows; Fig. 4, an enlarged view of the end of Fig. 1 containing the knives, showing the bottom and top knives and other details 40 in dotted lines; Fig. 5, a sectional view of a detail; Fig. 6, a horizontal section showing the side knives; and Fig. 7, a sectional view taken on the line 7 7 of Fig. 6, showing the manner of adjusting the side knives.

45 A is a table upon which the machine is supported.

B is the bed of the machine, secured upon the table A and provided with a longitudinal central recess, t.

50 C is a sliding block provided on its under

side with a tongue, t', forming its guide, which fits within the recess t, and on its upper side with an upward-projecting tongue, t'', broadest at its base, and tapering upward throughout part of its extent, the remainder of which 55 has vertical sides.

D is an oblong block or casting of dimensions coinciding with the bed B of the machine and resting upon the latter. The under side of the block D is cut out to leave the 60 space s of a height corresponding with that of the sliding block C, to receive the latter and permit it to reciprocate within the space s, and the upper side is cut or cast to produce the transverse zigzag form shown in Fig. 3. 65 A longitudinal slot, t', of the form of the tongue t'', and of dimensions to admit the latter within it and produce a snug fit, is provided in the part D.

E is a flat oblong block or casting of dimensions corresponding with those of the block D, and having its under side formed to coincide partly with the shape of the upper surface of the part D, but having a longitudinal recess, m', formed underneath it to receive the plate 75 E', by means of which the recess m is adjusted, and provided at one end with an upward projection, r, to receive a set-screw, q, the purpose of which will hereinafter be explained.

The block E is provided longitudinally with 80 a slot, p', like the slot t' in the part D, to admit the tongue p'' of the sliding grip-block F, reciprocating upon the top surface of the part E, the tongue p'' resembling in appearance the tongue t' on the block D, though differing from 85 the latter in its construction. The narrower and lower part of the tongue p'', having the vertical sides, instead of forming a part or extension of the tongue, as is the case with the tongue t', is inserted into an opening formed 90 to receive it in the part of the said tongue having the oblique sides, as shown in Fig. 3 of the drawings, and contains toward its upper extremity two balls, o, one formed upon the end of each of the set-screws n, and lying 95 each within a recess formed to receive it in the upper side of the narrow portion of the tongue p'', the arrangement being such that the portion last referred to of the tongue p'' may be raised and lowered by turning the set-screws 100

n. A central longitudinal recess, m , is formed on the under side of the block E to receive the articles to be shaved, as hereinafter described. The sliding block F is connected with the 5 sliding block C by means of pivoted links l .

G is a wheel provided with peripheral gearing, in which the pinion H upon the shaft x^2 , driven by steam-power, operates to revolve it.

I is a pitman pivoted at one end to the 10 wheel G, as shown, and at its opposite end to a plate, j , preferably of the form clearly shown in Fig. 1 of the drawings, which plate j is firmly secured to the sliding block C.

K and K' are knives, the one K projecting 15 obliquely downward and forward through an opening provided through the part E, and the other projecting upward to cause its edge to meet that of the knife K at the recess m , as shown, through the parts underneath the 20 part E.

K² and K³ are the side knives.

The operation of the parts thus far described is as follows: The sliding blocks F and C being in a position somewhat farther toward the 25 left-hand end of the machine than is shown in Fig. 1 of the drawings, so far that the block C will abut against the end of the slot s , the links l , joining the two blocks, will have been caused, by the mechanism hereinafter described, in the backward movement of the 30 blocks, to assume vertical positions, and the device will be ready to operate upon the article to be shaved, which is inserted into the recess m from the end of the machine far enough to cause part of it to lie between the tongues t^2 and p^2 of the blocks C and F. The wheel G, revolving in the direction of the arrow shown in Fig. 1, will, through the medium of the intervening mechanism already described, 35 cause the blocks C and F to move toward the knives; but the pitman I being connected directly only with the block C and not with the block F, the block C will be moved forward slightly in advance of the block F, causing 40 the links to assume an oblique position, whereby the article operated upon will be firmly pressed by the tongue p^2 against the upper surface of the tongue t^2 , and moved forward by the friction produced until its forward end 45 reaches the knives, the length of the pitman's stroke being sufficient to bring the article to the knives but not between them.

As will hereinafter be seen, the first article to be shaved, just referred to, is driven between 50 the knives by being pushed by the next article which is inserted into the recess m , and carried or pulled forward in the manner described of the first article, when the blocks C and F shall have been returned to their position 55 at the end of the machine necessary to enable them to perform the operation. When the blocks C and F shall have brought the article to be shaved to the position before the knives just described, it is necessary that they shall 60 be returned, leaving such article in its position, to cause them to do which they must be

relieved from their frictional contact with it. This is effected by the mechanism of which the following is a description:

L is a rod or bar secured to the vertical 70 plates f^2 and lying along the edge of the table. A reciprocating plate, h , is secured upon the bar L, and is connected with the plate j by means of pivoted links h' , h^2 , and h^3 . The link h^2 , which forms the connection between 75 the upper corner of the plate j and the plate h by its pivotal connection with the link h' , has an extension, h^4 , forming an angle with it and projecting upward from the pivotal point of the link h^2 , the end of which extension is 80 forked to receive a pivot, x , in the side of the block F.

On the rear surface of the wheel G a cam, G', is produced by forming the recess g . (Shown in dotted lines in Fig. 1.) A lever, M, pivoted 85 toward its center to one edge of the table, communicates at one end with the cam by means of a roller, y , moving within the recess g , and at its opposite end it is pivoted to the lever N, formed, for the sake of convenience, in two 90 parts, z and z' . On the under side of the table blocks O and O' are secured transversely, to provide bearings for the rods f , supported within longitudinal recesses formed on their lower surfaces by the plates f^4 , bolted to the 95 said blocks. Angular links f' are pivoted each at one end to the part z' of the lever N, and at their opposite ends each to one end of a plate, f^2 , of which there are two, each secured to the rod or bar L, and passing upward 100 through guides f^3 on the blocks O and O'. It should here be stated that the links l , h' , h^2 , h^3 , f' , plates j and h , rod or bar L, and parts f^2 , f^3 , and f^4 are also provided and arranged to operate in the manner shown on the side of the 105 machine presented to view in Fig. 1 on its opposite side, and that the pitman I is forked at about the point x' , the prong (not shown) extending to and being connected with a plate, j , in the manner shown of the prong represented in the said figure.

The operation of the mechanism just described is as follows: When the sliding blocks F and C shall have been drawn in the direction toward the wheel G as far as the stroke of the 110 pitman I will permit, the narrowed portion g' of the recess g around the cam G' will have come into contact with the roller y , causing the end of the lever M opposite the roller y to be thrown in the direction corresponding with 115 that of the wheel's motion, whereby the lever N will be forced in the same direction, causing the bell-crank levers or links f' to raise the rod or bar L, and with it the plate h , with which the sliding block F is connected by the pivoted 120 links h' and h^2 , and by means of the forked end of the latter operating against the pivot x in the block F, which it surrounds, the block F is moved to cause the links l to assume vertical 125 positions. In this way the article to be operated upon is released from frictional contact 130 with the surfaces of the tongues t^2 and p^2 , and

the blocks C and F slide back to the opposite end of the machine, by which time the point g^2 of the recess g will be in contact with the roller y , when the lever M will be moved in the direction opposite to that just described, pulling the rod or bar L downward and setting the links l in oblique positions, for the purpose already described. The knife K is firmly secured in its oblique position by means of a screw, e , 5 passing through a slot in its shank and into the material of the part E, and is thereby rendered adjustable upon the same angle to permit it to be raised and lowered to act upon leads or other articles to be shaved of different thicknesses by means of the set-screw mechanism 10 acting within the lug e^2 . The knife K' is adjusted by means of the set-screw e^3 and the finger e^4 , pivoted toward one end to the part D, and having an annular head, e^5 , forming a nut, 15 in which the screw e^3 turns. By means of the screw e' , screw e^3 , and finger e^4 the knives K and K' are held firmly in their positions. The curved dotted lines d and d' represent recesses leading from the edges of the knives K and 20 K' to the upper and lower surfaces of the machine, through which recesses the shavings from the leads may be automatically removed. The knives K² and K³ are inserted obliquely into openings formed to receive them—one in 25 each side of the machine. The cutting-edges of the side knives are arranged one at each side of the recess m ; as shown in Fig. 6, to lie slightly forward of the cutting-edges of the knives K and K', for the reason that the side 30 knives leave ragged edges upon each side of the lead or other article being shaved, which, owing to the position of the knives K and K', are removed by these latter. The form of the side knives is preferably that shown in Fig. 35 6, whereby they may be rendered laterally adjustable with relation to the recess m by means of screws k' , or set-screws working in openings provided to admit them in the vertical portions k of the said knives and entering 40 the side of the device. Their vertical adjustment is effected through the medium of a rod, k^2 , shown in Fig. 7 as inserted vertically into an opening in the machine from the top and bent toward one extremity. The bent end 45 lies underneath the shank of the knife, which is lowered and raised by means of the nut k^3 working upon the screw-thread formed upon the upper portion of the rod k^2 . Like the knives, the recess m is necessarily adjustable, 50 as shown in Fig. 3, in height as well as in width, to admit the leads and other articles of different dimensions. The height of the recess m is adjustable by means of the set-screws q , q' , and q'' , (shown in Fig. 1,) the first of 55 which has hereinbefore been described, the second operating within a slot, q^3 , through a plate, c , serving to connect the parts E and D together, and the third operating in a slot, q^4 , through a plate, c' , also serving to connect 60 the parts E and D together. The width of the slot is regulated, as hereinbefore stated, by means of the plate E' in the recess m' . The vertical set-screws m^2 , operating in elongated openings, serve to raise and lower the plate E' when the height of the recess m is regulated 70 by raising and lowering the casting E, as hereinbefore described, and horizontal set-screws m^3 serve to move the plate E' forward and backward in the recess m' to adjust the width of the recess m for leads and the other articles referred to of varying widths. It should here be stated that the limits within which the adjustable features hereinbefore described require to be adjusted to regulate the width of the recess m are very narrow, never 75 exceeding, at the very outside, about an eighth of an inch. 80

As hereinbefore described, the foremost lead or other article to be shaved is pushed between the knives by the article which follows it. These articles may be fed to the machine by hand or automatically, and for the latter operation I have provided an automatic feeding device, (shown as attached to the end of the machine in Fig. 2 of the drawings,) of 85 which the following is a description. 90

P is a long, narrow box of the width or about the width of the leads, &c., which are piled one upon the other within it. The box is supported upon the table A by means of 95 the brace b.

Q is a bar secured at one end to the end of the tongue t' of the sliding block C, of a length corresponding with that of the stroke of the pitman I. The bottom of the box P, which 100 is on a level with the lower side of the recess m , is provided with a central slot, a' , extending along its whole length, through which a finger, a , secured upon the rear end of the bar Q, projects. As the sliding block is moved 105 forward, and with it the bar Q, the finger a will move the lowest lead or other article into the recess m , and continue the operation as the block C is reciprocated, thus feeding the machine automatically. 110

The position of the knives might be arranged toward the end of the machine opposite to that at which they are shown, in which case the leads would be drawn instead of being pushed between them, and this arrangement 115 is included in my invention.

What I claim as new, and desire to secure by Letters Patent, is—

1. A machine for shaving printers' leads, slugs, and furniture, having a recess, m , to receive and confine the articles to be shaved, and having knives operating to shave the said articles when passed between them, in combination with clamping mechanism for moving the said articles forward within the recess m , and mechanism for reciprocating the said clamping mechanism, all substantially as described. 120
2. A machine for shaving printers' leads, slugs, and furniture, having a recess, m , to receive and confine the said articles to be shaved, and having knives arranged toward one end of the said recess to shave the said articles when passed between them, clamping 125
3. A machine for shaving printers' leads, slugs, and furniture, having a recess, m , to receive and confine the said articles to be shaved, and having knives arranged toward one end of the said recess to shave the said articles when passed between them, clamping 130

mechanism operating to carry the said articles in the said recess m toward the said knives, and reciprocating mechanism operating to move the said clamping mechanism back toward the inlet of the recess m after the said clamping mechanism shall have carried one of the said articles in a position before the knives, and to cause the said clamping mechanism to draw another article within the recess m , by means of the impingement of which against the first-named article the latter shall be forced between the knives, substantially as described, and for the purpose set forth.

3. A machine for shaving printers' leads, &c., comprising, in combination, the following elements, viz: a bed, B, provided with a longitudinal recess, t , on its upper side, a clamping-block, C, provided on its under side with a tongue, t' , fitting within the recess t , and upon its upper side with a tongue, t' , a block, D, secured toward each end upon the bed B, and hollowed out on its under side to produce the recess s , to receive the clamping-block C, and provided with a longitudinal slot, t^3 , to receive the tongue t^2 of the clamping-block C, a block, E, above the block D and adjustably connected with the same, and provided on its lower side with a recess, m , and with a longitudinal slot, p^3 , a clamping-block, F, upon the part E, and provided on its lower side with an adjustable tongue, p^2 , within the slot p^3 , adjustable knives K, K', K², and K³, having their cutting-edges arranged with relation to each other and to the recess m , as described, to shave the said printers' articles when passed between them, and mechanism operating to reciprocate the said clamping-blocks C and F, to carry the said articles along the recess m and pass them between the knives, as and for the purpose set forth.

4. In a machine for shaving printers' leads, &c., the combination, with the clamping-blocks C and F, of mechanism to reciprocate

the said blocks and cause them to clamp the object to be shaved in its forward motion with- 45 in the recess m , said mechanism comprising the following elements, viz: a wheel, G, pro- 50 vided with means for revolving it, a plate, j , secured to the clamping-block C and connected with the wheel G, a cam G', formed upon one face of the wheel G, pivoted links l , connect- 55 ing the clamping-blocks C and F, and mech- 60 anism connecting the cam G' and the plate j , whereby the clamping-block C is caused to move forward in advance of the clamping-block F, and whereby the said clamping-blocks C and F are returned with the links l in a vertical position, the whole being con- 65 structed and arranged to operate substantially as and for the purpose set forth.

5. The combination, with a machine for shaving printers' leads, &c., provided with a recess, m , to receive and confine the articles to be shaved, and having knives operating to shave the said articles when passed between them, and clamping mechanism for moving the said articles forward within the recess m , and mechanism for reciprocating the said clamping mechanism, of means for feeding the said articles automatically to the said ma- 70 chine, all substantially as described.

6. In a machine for shaving printers' leads, &c., the combination, with the tongue t' of the clamping-block C, of a rod or bar, Q, re- 75 ciprocating with the said tongue t' , having a finger, a , toward one end, and a box, P, sup- 80 ported upon the said machine and to contain the articles to be shaved, and provided with a longitudinal slot, a' , through which the finger a projects, substantially as described, and for the purpose set forth.

WILLIAM F. KLOSE.
